UNITED STATES PATENT OFFICE.

PATRICK T. SHIELDS, OF SAN ANTONIO, TEXAS.

FIREPROOF FLOOR CONSTRUCTION.

SPECIFICATION forming part of Letters Patent No. 738,496, dated September 8, 1903.

Application filed September 27, 1902. Serial No. 125,121. (No model.)

To all whom it may concern:

Be it known that I, PATRICK T. SHIELDS, a citizen of the United States, residing at San Antonio, in the county of Bexar and State of Texas, have invented a new and useful Fireproof Floor Construction, of which the following is a specification.

My invention is an improvement in the construction of fireproof flooring, and has for its object the construction of such a floor in a durable and substantial manner at a comparatively moderate cost.

I am aware of the fact that concrete has been used heretofore in various ways in the construction of fireproof building; and my invention consists, mainly, in the means for supporting and bracing the flooring.

In the accompanying drawings, Figure 1 is a sectional view showing my improved flooring. Fig. 2 is a plan view. Fig. 3 is a perspective view showing the manner of securing the tie-rods on a partition-wall. Fig. 4 is a detail of an anchor, and Fig. 5 is a modified form of anchoring the rods.

In the construction of my flooring anchors A, preferably V-shaped and having their ends A' bent at a right angle to the body of the anchor, are embedded in the outer or main walls B of the building, the anchors of one wall being in the plane of but out of alignment with the anchors of the opposite wall.

Divisional walls C, but one of which is shown in the drawings, are carried up to the level of the under surface of the proposed flooring and then extending about one brick higher in the center, as shown at C'.

Steel tie-bars D have their outer ends bent around the end members A² of the anchors, these end members projecting into recesses B', formed in the walls B. The tie-rods are then bent downward for a short distance, as at D', and carried across the building to a point adjacent the first divisional wall and then bent upward and carried over and around a steel bar E, as shown at D². The steel bar E rests on the raised central portion C' and extends the length of same. From the opposite wall extend similar tie-rods D³, which are bent around the bar E, intermediate the rods D. After the rods are placed in position a flooring of concrete is laid in a plastic state and supported by stages, in the

usual manner, until hardened. In practice I make this concrete layer between five and six inches in thickness, but the exact dimensions of the various parts would vary according to the size of the building. Upon this concrete and intermediately over the wall C is placed the upper divisional wall C², which supports the floor above. On the concrete and parallel to the walls B C² are placed strips F, which may be of either wood or metal, and resting on and secured to these strips is the flooring G, which is preferably of hard wood, although it may be of any desired material. An air-space H is left between the flooring and the concrete intermediate the strips.

In Fig. 5 I have shown a modified form of anchor for the side walls comprising a steel bar I, similar to the bar E, the tie-rods being secured to it in the same manner as to the anchors A, and intermediate each tie-rod an anchor J has one end bent around the bar I and the opposite end bent at an angle and 75 embedded in the wall.

It is understood, of course, that the concrete fills the recesses B' and extends across the building through as many divisional walls as may be used.

Having thus fully described my invention, what I claim as new, and desire to secure by Letters Patent, is—

1. In a building, the combination with side and divisional walls, of tie-rods anchored at one end in the side walls their inner ends resting upon the divisional walls, a concrete flooring extending through the divisional walls to the side walls, and means for securing the inner ends of the tie-rods to the divisional walls.

2. In a fireproof building, the combination with side and divisional walls, of a bar resting lengthwise of the divisional wall, tie-rods anchored at one end to the side walls and 95 bent around the bar at the divisional wall, of a layer of concrete resting on said tie-rods and extending across the divisional wall, and of an upper divisional wall resting on the concrete above the first and adapted to support 100 a second flooring.

3. In a fireproof flooring, the combination with recessed side walls, of a divisional wall, anchors embedded in the side walls and pro-

jecting into the recesses, a bar resting on the divisional wall, tie-rods secured to the side walls at one end by the anchors and bent around the bar at their opposite ends, a layer 5 of concrete supported by the tie-rods and extending across the divisional wall and into the recesses of the side walls, strips laid on said concrete, and a flooring supported by said strips.

10 4. In a fireproof building having side and divisional walls, the combination with the recessed side walls, of bars running longitudinally along said recesses, anchors secured at

one end to said bar and embedded in the said walls at the other end, a bar resting on the divisional wall, tie-rods secured at one end to the bars in the recesses and at the other end to the bar of the divisional wall, a layer of concrete resting on said tie-rods and extending from one side wall to the other, and a supplemental flooring laid on the concrete. 15 20
